UNITED STATES PATENT OFFICE.

IRA W. FOLTZ, OF CHICAGO, ILLINOIS, ASSIGNOR TO THE EUREKA SMOKELESS FURNACE COMPANY, OF CHICAGO, ILLINOIS, A CORPORATION OF ILLINOIS.

FURNACE APPLIANCE.

1,208,123.

Specification of Letters Patent. Patented Dec. 12, 1916.

Application filed June 21, 1915, Serial No. 35,333. Renewed April 6, 1916. Serial No. 89,484.

To all whom it may concern:

Be it known that I, IRA W. FOLTZ, a citizen of the United States of America, and a resident of Chicago, county of Cook, and State of Illinois, have invented certain new and useful Improvements in Furnace Appliances, of which the following is a specification.

This invention relates to gas burning devices which may be applied to many furnaces of standard construction, but which are ordinarily of low efficiency in regard to the combustion of gases given off by burning or coking coal, resulting in the production of smoke and soot.

The main objects of the invention are to provide an appliance of this nature arranged to divide such furnaces into gas-producing and gas-consuming regions and constructed to supply air to the gas-consuming region in proper or variable quantities with respect to the air supplied to the gas-producing region to insure a high degree of combustion, regardless of the condition of the fire-bed and quantity of coking coal therein; to provide an improved construction for supplying air to furnaces; to provide gas burners which may be applied to coal furnaces; to provide an improved means for regulating the draft or air supply to such burners; and to provide a construction for furnaces permitting the desired intercommunication between various parts of the fuel body and the air supply and the gas burning region.

An illustrative embodiment of this invention is shown in the accompanying drawings, in which—

Figure 1 is a transverse vertical section of a furnace constructed according to this invention. Fig. 2 is a longitudinal vertical section of the fire-box. Fig. 3 is a detail in side elevation of the air supply and gas burning device. Fig. 4 is a detail in section taken on the line B—B of Fig. 3. Fig. 5 is a plan view of the air supply and gas burning device. Fig. 6 is a section taken on the line A—A of Fig. 5.

Furnaces of the general type shown in the drawing, but without the present improvements, are usually constructed to permit a direct draft to pass from the ash-pit upward through the grate and coal body and from there to pass freely through the combustion chamber to the chimney. Thus, the

gases given off by the burning and coking coal are carried directly through the furnace in greatly unconsumed condition, their heating value being mainly lost. The present construction serves to retard the flow of gases above the fire in order that the same may be highly heated and brought to the ignition point in temperature. Large quantities of heated air are supplied to the burning coal at the sides and top thereof and the same becomes mixed with the gases. The pressure of the gases and the action of the draft then cause the unconsumed gases to pass to the combustion chamber or zone of great heat, to which an additional supply of hot air is delivered, thus insuring very complete combustion of the gases.

A well known type of furnace is shown, comprising a boiler 1 surrounding the fire-box 2 and inclosed by the usual brick-work 3. The construction of the grate 4 and arrangement of flues 5 in the combustion chamber are shown as the same usually occur in this type of furnace. The new construction in Figs. 3 to 5 comprises a plurality of air conduits 6, 7, 8 and 9 suitably constructed to permit the free passage of air lengthwise therethrough and to receive air from the ash-pit 10 at the sides and ends of the grate 4. The conduits 6 and 7 which extend along the sides of the grate are narrow at their bases so that they may be supported by the grate rest 12 between the grate and the side walls of the furnace without interfering with the action of the grate. The strengthening webs 13 of the conduits have downwardly extending feet 14 for engaging the grate rest and are also cut away at 15 to permit the desired flow of air along the device. The upper surfaces 16 of the conduits are comparatively wide and are provided with a plurality of collars 17 in which are slidably mounted perforated tubes 18. Air enters the conduits 6, 7, 8 and 9 at the bottom, first traveling upward through the space between the grates and the walls of the fire-box and through the apertures in the grate rest.

Surrounding the tubes 18 are perforated tubes 19 having bell mouths 20 at their lower ends for encircling collars 17 which provide a support for the tubes. The inner surfaces of the bell mouths on tubes 20 have grooves 21 for receiving pins 22 on the collars, thus requiring that the tubes 19 be turned while

being lifted from the collars 17 for the purpose of normally preventing accidental displacement of the tubes. The tubes 18 may be moved relatively of the tubes 19 for the purpose of bringing the respective apertures in the tubes into or out of alinement to regulate the extent of through communication between the ash-pit and the fire-box 2. Movement of the tubes 18 is accomplished by means of inclined cams 23 carried by rods 24 slidably mounted in webs 13.

The operating handles 25 of rods 24 are located in convenient position near the ash-pit door of the furnace, as shown in Fig. 2. The rear ends of the conduits 6 and 7 support perforated tubes 26 which are similar in construction to the tubes 19, but are not shown as provided with any regulators, such as tubes 18, since it is desired to always maintain free communication between the air conduits and the combustion chamber 27. The conduits 6 and 7 also have upstanding hollow recessed members 28 for supporting an arch or baffle wall 29 which serves to separate the fire-box or gas-producing region 2 from the combustion chamber or gas-consuming region 27. The baffle wall 29 may be provided with a plurality of conduits 30 for carrying gases out of chamber 2 into a zone of great heat at the lower edge and rear of the baffle wall. The conduits 30 communicate with a transverse conduit 30.1 extending through the lower part of the baffle wall or arch. Outlets for the conduit 30.1 to the combustion chamber are provided at the rear of the arch and as near the center thereof as practicable. The conduit 30.1 receives air at its ends from the hollow members 28, thereby insuring thorough combustion of the gases which are carried from the furnace chamber downward through the arch, and also backward and upward through the fuel body between the lower edge of the arch and the grate. The conduit 9 carries a plurality of perforated upstanding tubes 31 similar to tubes 26, but preferably longer. The tubes 31 provide for supplying additional air at a point farther along the line of combustion than the location of tubes 26. The conduit 8 is shown as perforated on its upper surface to allow the passage of air to the fuel body at the front of the grate.

In the operation of the device, if there is sufficient coal on the grate to substantially close the space between the lower edge of baffle 29 and the grate, large quantities of combustible gases from the coal will pass mainly into the conduits 6 and 7 through the tubes 19 and are delivered to the combustion chamber through the tubes 26 and 31. A more direct line of draft is provided from the ash-pit to the combustion chamber through the tubes 26 and 31. Thus, a considerable quantity of fresh air is de-

livered to the combustion chamber independently of the air which passes through the fuel body. The fresh air which is delivered to the combustion chamber becomes heated in passing in under the grate and through the conduits and pipes, and when mingled with the gases also carried through the conduits 6 and 7, insures fairly complete combustion when the mixture reaches the zone of greatest heat at the rear of baffle 29. The combustion is further facilitated by the more or less pure air which finds its way to the combustion chamber directly from the ash-pit through the tubes 31.

The above described operation is greatly modified under different conditions of the coal body. For instance, if the firing door is open and the space between the baffle and the upper surface of the grate is choked by coal and ashes, air which works through the coal body passes into the tubes 19; together with more or less of the gas, while the conduits 30 in the baffle 29 also carry fresh air downwardly to a point of combustion at the lower edge and rear of the baffle, said air becoming mixed with the air and gases which are delivered through the tubes 26 and 31.

According to the respective area of the openings at the firing door or the ash-pit door and the extent of choking of the grate, the air may flow either upwardly out of the tubes 19 or downwardly through the tubes, ultimately finding its way into the combustion chamber. The gases may at times be traveling downward through the tubes 19, while air is traveling upward through some of the remaining tubes, depending upon the condition of the coal body and the pressure of the air and gases at different points. If there is a great quantity of coal and ashes on the grate, the normal upward draft through the grate is decreased and the fresh air is supplied mainly through the tubes 19 located at the sides of the coal body. If, under such conditions, it is desired to check the fire, the rods 24 may be pulled outwardly, thus raising the tubes 18 into position to close communication between said tubes and the tubes 19. It is well known that the sudden checking of the draft to the entire furnace containing a large body of coal and fire results in the creation of smoke and soot, since the heat of the fire continues to distil the gas for some time after the draft is cut off and where there is not sufficient air to consume the gases, large quantities of smoke and soot result. In the present construction, while the air supply to the coal body may be more or less stopped, the air supply to the gas burning region or the combustion chamber continues according to the draft in the chamber, which draft under such conditions in fact increases somewhat, since the only open path for the air is then

directly from the ash-pit through the tubes 26 and 31 to the combustion chamber. This results in the continued combustion of the gases after the checking of the fire.

5 It may be seen that the present construction provides means for supplying heated air at successive intervals along the line of combustion, thereby insuring very complete combustion. A perfect and natural 10 balance of the pressure of gases and of atmosphere is maintained in the furnace at all times whatever may be the quantity of fuel or of air.

Although but one specific embodiment of 15 this invention has been herein shown and described, it will be understood that numerous details of the construction shown may be altered or omitted without departing from the spirit of this invention as defined by the following claims.

I claim:

1. The combination with a furnace comprising a fire-box, ash-pit, and combustion chamber, of a removable attachment there- 25 for comprising a conduit adapted to be sup- ported at the inner sides of the fire-box, said conduit being provided with openings ar- ranged for communication respectively with the ash-pit, fire-box and combustion cham- 30 ber, and means for regulating the area of the openings in the conduit communicating with the fire-box.

2. The combination with a furnace comprising a fire-box, ash-pit, and combustion 35 chamber, of an attachment therefor com- prising a conduit adapted to be supported at the inner sides of the fire-box, said con- duct being provided with openings arranged for communication respectively with the 40 ash-pit, fire-box and combustion chamber, and a plurality of perforated upright pipes above the openings in the conduit communi- cating with the fire-box.

3. The combination with a furnace comprising a fire-box, ash-pit, and combustion chamber, of an attachment therefor com- 45 prising a conduit adapted to be supported at the inner sides of the fire-box, said conduit being provided with openings arranged for communication respectively with the ash- 50 pit, fire-box and combustion chamber, and a plurality of perforated upright pipes above the openings in the conduit communicating with the combustion chamber.

55 4. The combination with a furnace comprising a fire-box, ash-pit, and combustion chamber, of an attachment therefor com- prising an air conduit extending from the fire-box to the combustion chamber, said 60 conduit being provided with a plurality of perforated upstanding pipes extending into the fire-box and combustion chamber.

65 5. The combination with a furnace comprising a fire-box, ash-pit, and combustion chamber, of an attachment therefor com-

prising an air conduit extending from the fire-box to the combustion chamber, said conduit being provided with a plurality of perforated upstanding pipes extending into the fire-box and combustion chamber, and 70 means for regulating the relative effective area of the perforations in said upstanding pipes in the fire box and the combustion chamber.

6. A furnace structure having a fire box, 75 combustion chamber and ash pit, a grate structure beneath both said fire box and combustion chamber and separating said box and chamber from said ash pit, a baffle wall structure interposed between said com- 80 bustion chamber and fire box and extending downwardly to the normal top level of the fuel, said baffle wall having a hollow interior and having in its front wall ducts for connecting said hollow interior with the fire 85 box, and having ducts whereby said hollow interior communicates with the combustion chamber, and means for supplying fresh air to the interior of said baffle wall.

7. A furnace structure having a fire box, 90 combustion chamber and ash pit, a grate structure beneath both said fire box and combustion chamber and separating said box and chamber from said ash pit, a baffle wall structure interposed between said com- 95 bustion chamber and fire box and extending downwardly to the normal top level of the fuel, said baffle wall having a hollow interior and having in its front wall ducts for connecting said hollow interior with the fire 100 box, and having ducts whereby said hollow interior communicates with the combustion chamber, means for supplying fresh air to the interior of said baffle wall, and means for supplying fresh air to said fire box above 105 the grate.

8. A furnace structure having a fire box, combustion chamber and ash pit, a grate structure beneath both said fire box and combustion chamber and separating said box and chamber from said ash pit, a baffle wall structure interposed between said combustion chamber and fire box and extending downwardly to the normal top level of the fuel, said baffle wall having a hollow interior 110 and having in its front wall ducts for connecting said hollow interior with the fire box, and having ducts whereby said hollow interior communicates with the combustion chamber, and means for supplying fresh air 115 to the interior of said baffle wall, the hollow interior of said baffle wall serving as a mixing chamber for the gases from the fire box and the fresh air supplied to the interior of said baffle wall.

9. A furnace structure having a fire box, combustion chamber and ash pit, a grate structure beneath both said fire box and combustion chamber and separating said box and chamber from said ash pit, a baffle 130

- 4
- wall structure interposed between said combustion chamber and fire box and extending downwardly to the normal top level of the fuel, said baffle wall having a hollow interior 5 and having in its front wall ducts for connecting said hollow interior with the fire box, and having ducts whereby said hollow interior communicates with the combustion chamber, means for supplying fresh air to 10 the interior of said baffle wall, and means for supplying fresh air to said fire box above the grate, the hollow interior of said baffle wall serving as a mixing chamber for the 15 gases from the fire box and the fresh air supplied to the interior of said baffle wall.
10. A furnace structure having a fire box, combustion chamber and ash pit, a hollow baffle wall structure interposed between said combustion chamber and fire box and extending downwardly approximately to the 20 normal top level of the fuel, said baffle wall having openings leading from said fire box
- into its hollow interior, means for supplying fresh air to the interior of said baffle wall, and means for directing the mixture 25 from the interior of said baffle wall into the combustion chamber.
11. A furnace structure having a fire box, combustion chamber and ash pit, a hollow baffle wall structure interposed between said 30 combustion chamber and fire box and extending downwardly approximately to the normal top level of the fuel, said baffle wall having openings leading from said fire box into its hollow interior, means for supplying 35 fresh air to the interior of said baffle wall, means for directing the mixture from the interior of said baffle wall into the combustion chamber, and means for supplying fresh air to the fire box above the grate. 40

Signed at Chicago this 17th day of June, 1915.

IRA W. FOLTZ.
